UNITED STATES PATENT OFFICE.

GEORGE SKIDMORE, OF YOUNGSTOWN, OHIO.

FLOWER HOLDER.

1,402,904.

Specification of Letters Patent. Patented Jan. 10, 1922.

Application filed May 5, 1921. Serial No. 467,061.

To all whom it may concern:

Be it known that I, GEORGE SKIDMORE, a citizen of the United States, residing at Youngstown, in the county of Mahoning and State of Ohio, have invented certain new and useful Improvements in Flower Holders, of which the following is a specification.

This invention relates to an improved flower holder particularly designed for use upon articles of wearing apparel such as upon the lapel of a coat, and has as one of its principal objects to provide a device of this character employing a water receptacle for receiving the stem of a flower or a plurality of such stems whereby the flower or flowers, as the case may be, will be kept fresh.

The invention has as a further object to provide a flower holder embodying a separable attaching member which may be removably engaged with a garment, the water receptacle being removably engageable with the attaching member to be securely held thereby in position upon the garment.

A further object of the invention is to provide a device of this character wherein water contained within the receptacle will not readily splash therefrom.

And the invention has as a still further object to provide a flower holder which will be extremely neat and attractive in appearance and wherein the water receptacle will be normally concealed.

Other and incidental objects will appear hereinafter.

In the drawings:

Figure 1 is a perspective view illustrating the use of my device upon a coat lapel, the lapel being conventionally illustrated in dotted lines,

Figure 2 is an enlarged vertical sectional view through the device,

Figure 3 is a perspective view of the attaching member of the device, and

Figure 4 is a vertical sectional view illustrating a slightly modified form of receptacle and closure plug therefor.

In carrying the invention into effect, I employ a water receptacle 10, preferably of glass and of a size to render it inconspicuous in use. Disposed within the receptacle is a closure plug therefor comprising a head, 11 fitting tightly within the mouth of the receptacle and formed with a central flower stem receiving opening 12. Depending from the lower portion of the head into the re-

ceptacle is a flexible guard tube or nipple 13 surrounding said opening, the head and nipple comprising a unitary structure preferably formed of rubber. Encircling the upper end of the receptacle is an elastic collar 14 of rubber or the like gripping the receptacle and forming a guard for the rim thereof. As will be noted by reference to Figure 2, the collar 14 as well as the closure plug 65 lie flush with the rim of the receptacle and overlying said plug and collar is a facing ring 15 adhesively secured to the plug and collar, a central opening in the ring registering with the opening 12 in the closure plug. 70 The ring 15 provides a smooth and unbroken surface at the upper end of the water receptacle and serves to unite the plug and collar.

The separable attaching member of the 75 device is formed from suitable flat resilient sheet metal and includes a preferably split ring 16. Upstanding from said ring at one side thereof, preferably at a point diametrically opposite the split in the ring, is a 80 spring supporting loop 17 from which depends a shank 18, and projecting from said shank at opposite edges thereof, substantially in a plane with the ring, are lateral bearings 85 arms 19.

In Figure 1 of the drawings, I have shown the use of the device upon an ordinary coat lapel 20, said lapel being formed with the usual buttonhole 21. In practice, the receptacle 10 is, of course, filled with a suitable quantity of water. The attaching member is then engaged with the coat lapel 20, the ring 16 being passed through the buttonhole 21 from the front of the lapel so as to lie snugly against the coat at the rear thereof. The member is then pulled downwardly to engage the side portions of the loop 17 with the front and rear faces of the lapel, the bight of the loop resting upon the lower side of the buttonhole and the shank 18 100 lying at the outer side of the lapel. As will be appreciated, due to the resiliency of the material from which the attaching member is made, the sides of the loop will grip the lapel so that the attaching member will thus 105 be firmly yet removably secured in position. The shank 18 with its laterally projecting arms 19 frictionally coacts with the front of the lapel to prevent upward movement as well as sidewise shifting and tilting of the 110 attaching member. When the attaching member has been placed in position, the re-

ceptacle 10 is lowered through the ring 16 of said member and the ring engaged about the collar 14 of the receptacle for removably connecting the receptacle with the attaching member. As will be readily understood, the ring resiliently grips the collar and frictionally coacts therewith to afford a firm connection. After the receptacle has been connected to the attaching member in the manner just stated, the stem of a flower may be inserted through the buttonhole and through the closure plug of the receptacle for immersing the stem at its lower end in the water within the receptacle. Thus, the flower will be kept fresh while the flexible guard nipple will frictionally coact with the stem of the flower to prevent upward displacement thereof. Furthermore, by employing a closure plug of the type disclosed, liability of splashing of water from the receptacle will be reduced to a minimum.

It is contemplated that in the manufacture of the device, the attaching member will be finished in an attractive manner, the bearing arms being formed, as indicated in Figure 3, to simulate leaves, such as rose leaves, and the shank 18 being formed to represent a stem carrying the leaves. Thus, a highly pleasing effect will be achieved while the water receptacle will be hidden from view behind the coat lapel. Furthermore, while I have shown the use of a split ring for the attaching member, it is to be understood that, if desired, said ring may be unbroken.

In Figure 4, I have illustrated a slightly modified form of receptacle and closure plug therefor wherein the receptacle is formed at its upper end with an annular lip 22. As in the preferred embodiment of the invention, I employ a preferably rubber closure plug including a depending longitudinally tapered nipple 23 fitting within the mouth of the receptacle and a head 24 overlying the lip. Depending from said head to snugly surround the lip is a collar 25 corresponding to the collar 14 of the preferred construction, and projecting inwardly from the lower end of said collar is an annular flange 26 engaging beneath the lip of the receptacle for firmly securing the plug in position.

Having thus described the invention, what is claimed as new is:

1. A flower holder including a receptacle,

a closure plug having an apertured head fitting in the receptacle and provided with a depending guard nipple surrounding the aperture therein, a collar surrounding the receptacle, and an attaching member for the receptacle coacting with said collar.

2. A flower holder including a receptacle, an apertured plug closing the receptacle, a collar surrounding the receptacle, the plug and collar lying flush with the rim of the receptacle, a facing ring overlying the plug and collar connecting said plug and collar and having an opening registering with the aperture of the plug, and an attaching member for the receptacle coacting with said collar.

3. A flower holder including a receptacle, an apertured closure therefor, and an attaching member for the receptacle comprising a ring embracing the receptacle and having a spring supporting loop rising therefrom and continued to form a shank depending from said loop, the shank having lateral bearing arms projecting at opposite edges thereof.

4. A flower holder including a receptacle, an apertured closure therefor, and an attaching member for the receptacle comprising a split ring embracing the receptacle and having a spring supporting loop rising therefrom at a point diametrically opposite the split in the ring, the loop being continued to form a shank depending from said loop and having lateral bearing arms projecting at opposite edges thereof substantially in a plane with the ring.

5. In a flower holder, the combination of a receptacle, an apertured closure plug including a head fitting tightly in the receptacle and a flexible guard nipple depending from the head into said receptacle, and an attaching member for the receptacle including a ring embracing the receptacle and a spring supporting loop upstanding from said ring whereby the attaching member may be removably clamped upon a garment by said loop, there being a shank depending from the loop and having lateral bearing arms, said shank and arms being adapted to frictionally coact with the fabric of the garment for preventing either upward or side-wise shifting of the attaching member.

In testimony whereof I affix my signature.
GEORGE SKIDMORE. [L. s.]
